TILTING BRACKET FOR CONTAINERS

Nikolai Martinsen, Palo Alto, Calif.

Application May 10, 1948, Serial No. 26,102

10 Claims. (Cl. 248—139)

1

This invention relates to tilting brackets for supporting dispensing receptacles, such as for example cans, bottles, casks and other like containers. More particularly this invention relates to a tilting wall bracket adapted to be attached to a vertical support, such as a wall, to normally support a receptacle or container in an upright position for storage convenience, and to support the receptacle or container when the bracket and container are tilted during pouring or dispensing operations.

The principal object of this invention is to provide a tilting bracket for dispensing receptacles which may be rigidly attached to a vertical support, such as a wall, to facilitate the pouring or dispensing of contents from a container of the type which has a dispensing spout or mouth located adjacent the top thereof. It is contemplated that a bracket constructed in conformity with the invention to be more fully described may be advantageously used in garages, service stations, laboratories, laundries, and other places where liquids (as for example, oil, kerosene, cleaning solvent, chemicals, distilled water, or liquid soap) are frequently dispensed from containers capable of manual handling.

Another object of this invention is to provide a tilting bracket having its parts arranged to neatly fold into a compact package for convenient storage and shipment.

Another object of this invention is to provide a tilting wall bracket for dispensing receptacles which may be installed conveniently in a shop or home by the user thereof to serve as a neat and attractive storage place for receptacles.

Another object of this invention is to provide a tilting bracket having adjustable means to readily facilitate rapid attachment to or removal from containers.

Another object of this invention is to provide a tilting bracket having means adapted to rigidly support containers of varying sizes, such as rectangular cans, or round bottles, or the like.

A further object of this invention is to provide a tilting wall bracket for containers which is simple in construction, inexpensive to manufacture, and which is easy to install.

Further objects of this invention will become apparent upon the reading of the following specification and referring to the accompanying drawings in which similar characters of reference represent corresponding parts in each of the several views.

Fig. 1 is a perspective view of the bracket with a dispensing receptacle (indicated in broken lines) supported therein.

2

Fig. 2 is a top plan view of the bracket and receptacle therein supported in pouring position.

Fig. 3 is a sectional view taken on line 3—3 of Fig. 2.

5 Fig. 4 is a side elevational view of the bracket and container in upright position.

Fig. 5 is a side elevational view of the bracket having bottle holding means to support a bottle.

Fig. 6 is a top plan view of the bracket and bottle holding means illustrated in Fig. 5.

10 Fig. 7 is a perspective view of the bracket in folded position.

Referring now more specifically to the drawings the tilting bracket comprises a pair of identical trackways, such as oppositely facing channel pieces 8 and 9, held in rigid parallel spaced relationship to one another by upper and lower transverse frame pieces 11 and 12 which are attached at their respective ends to the channel pieces in any suitable manner, such as by welding, bolts, or the like. A substantially rectangularly-shaped receptacle supporting member, indicated generally at 13, having marginal upwardly extending flanges 14, is provided with a pair of ears 15 which depend below the bottom of the supporting member to support track runners 16 which may be rotatably mounted on pins or axles 17 carried by said ears. The runners 16 are located on opposite sides of supporting member 13 adjacent the rear end thereof and nest within the channel openings of the channel pieces and arranged for vertical slidable track movement within the said channel pieces.

15 Each side of supporting member 13 is provided with a pair of apertures 18 through which the hooked ends 19 of V-shaped supporting rods or arms 21 may be pivotally attached. The sides of V-shaped supporting arms 21 nearest the channel pieces 8 are formed with a crimp 22

20 adapted to engage pivotally hooks or eyelets 23 of the frame supporting arms 24 which are in turn pivotally connected to the channel pieces 8 and 9 by means of hooks 25 which are pivotally connected to each channel piece adjacent the tops thereof.

25 An elongated rectangular can or container, such as a five (5) gallon kerosene can, indicated generally at 26 in the drawings may be securely but removably supported in the receptacle supporting frame 13 by a pair of identical clamping arms 27. The clamping arms 27 each comprise a rod having a hook or eye 28 which pivotally engages a crimp 31 provided in the V apex of V-shaped supporting arm 21. Each rod carries slidably a V-shaped clamping member 32. The inwardly extending tops of V-shaped clamping

members 32 are bent downwardly as indicated at 33 to engage securely a top marginal bead 34 of the can or container. Clamping arms 27 are preferably threaded to receive a thumb screw 35 or the like utilized to effect a clamping action of member 32 upon the bead 34 and the top of the container 26. The container 26 is adapted to nest within flanges 14 to prevent displacement of the bottom portion thereof relative to the bracket during tilting.

Referring more specifically to Figs. 5 and 6 I have illustrated how a container, such as a distilled water bottle 39, may be supported in a bracket of the type described above. In view of the fact that a receptacle, such as a bottle, does not have a flat top or marginal bead upon which the V-shaped clamping members 32 may act, I prefer to provide an annular band 36 arranged to fit around and upon the shoulder portion 37 of the bottle. This annular band serves as an engaging member to which the clamping members 32 are connected.

In operation the bracket is rigidly affixed to a vertical support, such as a wall, by means of screws or bolts 40 which extend through holes 38 provided in transverse member 11. The dispensing receptacle may be placed in and supported in upright position by support frame 13 and held firmly in position by clamping arms 27. When it is desired to pour the contents from the receptacle, the operator need only manually pull the top of the receptacle toward him to the desired tilting or pouring position. The pivotal connection 22 and 23 is substantially the axis about which the supporting member 13 tilts. It is apparent that when the container and frame therefor are tilted forwardly the bottom of the container and rear of the frame 13 move with runners 16 vertically upwardly along channel pieces 8 while simultaneously the forward end of supporting frame 13 and top of the container are tipped downwardly. The downwardly inclined tilted position whereby the top of the container is below the horizontal is made possible by the depending ears 15 which carry the track engaging runners 16.

Referring to Fig. 3 it will be readily understood that because runners 16 depend below the bottom edge of support member 13 of the bracket the pouring spout of the receptacle in tilted position is lower than the bottom of the container, thereby insuring maximum pouring efficiency.

I have illustrated the various link connections between members 21, 24 and 27 as operating on a "hook and eyelet" principle, and although I do not confine myself to this particular manner of attachment, the hook and eyelet connections afford an advantage in that the several connections may be folded inwardly to form a compact package for purposes of shipment, and storage or the like (Fig. 7). Members 21 and pivotally attached arms 24 and 27 may fold inwardly toward one another while support 13 folds upwardly toward said channel pieces to enclose said members and arms therebetween (Fig. 7).

Although I have described my invention in rather specific detail by way of example and illustration for purposes of clarity of understanding, it is understood that changes and modifications in design, use, installation and structure may be practiced within the spirit of the invention and the scope of the appended claims.

I claim:

1. A tilting bracket for containers comprising a pair of rigid spaced parallel channel mem-

bers forming trackways, a container support frame, a first set of pivotal connections for said frame comprising track runners supported by said frame at one end thereof and engaged slidably and tiltably in said trackways, and a second set of pivotal connections for said frame, each part of said second set of pivotal connections being arranged to connect said frame forwardly of said runners pivotally to a said channel member adjacent the top thereof.

2. A tilting bracket for containers comprising a pair of rigid spaced parallel channel members forming trackways, a container support frame, a first set of pivotal connections for said frame comprising track runners supported by said frame at one end thereof and engaged slidably and tiltably in said trackways, and a second set of pivotal connections for said frame, each part of said second set of pivotal connections being arranged to connect said frame at a point forwardly of said runners pivotally to a said channel member adjacent the top thereof, and container clamping arms carried by said frame.

3. A tilting bracket for containers comprising a pair of spaced vertical rigid channel members forming trackways, a frame member to support a container, a first set of pivotal connections for said frame comprising a pair of ears carried by said frame at one end thereof and depending downwardly therefrom, runners carried by said ears and slidably and tiltably engaged in said trackways, and a second set of pivotal connections for said frame, each part of said second set of pivotal connections comprising a link connected pivotally to the top of each channel member, supporting arms carried by said frame on opposite sides thereof, each link connected pivotally to a supporting arm, and container clamping means carried by each said supporting arm.

4. A tilting bracket for containers comprising a pair of spaced vertical parallel channel members forming trackways, a container supporting frame disposed normally at substantially right angles to said channel members, a first set of pivotal connections for said frame each part of said first set comprising a slidable pivotal connection to connect said frame to said channel members, a second set of pivotal connections for said frame arranged to limit pivotal movement of said frame relative to said channel members beyond a predetermined point, and means carried by said frame to attach a container removably thereto, said frame slidably and pivotally movable relative to said channel members from a position substantially normal to said channel members through an arc of at least 90° relative thereto.

5. A tilting bracket according to claim 4 and wherein said slidable pivotal connection to connect said frame to said channel members is disposed below the bottom of said frame whereby said frame is tilted downwardly in the direction of length of a container supported therein when said frame is moved slidably and tiltably relative to said channel members to a position of maximum predetermined movement.

6. A tilting bracket for containers comprising a pair of spaced parallel vertical rigid channel members forming trackways, a frame to support a container, a slidable pivotal connection to connect one end of said frame slidably and pivotally to said channel members, a pair of substantially V-shaped supporting arms connected pivotally to opposite sides of said frame, container clamping arms connected pivotally to said V-shaped

arms, and other pivotal connections to connect pivotally said channel members to said supporting arms.

7. A tilting bracket according to claim 6 and wherein said slideable pivotal connection to connect said frame to said channel members is disposed below the bottom of said frame whereby said frame is tilted downwardly in the direction of length of a container supported therein when said frame is moved slideably and tiltably relative to said channel members to a position of maximum predetermined movement.

8. A tilting bracket for containers according to claim 6 and wherein an annular member arranged to be positioned over a container supported in 15 said frame is connected releasably to said container clamping members.

9. In a tilting bracket for containers having a rigid main frame and a tiltable container support frame, the improvement which includes a 20 track channel formed in said main frame, a first pivot attached to one end of the container support frame and engaged slideably and pivotally with the track channel in said main frame, a supporting arm spaced from said first pivot and connected to said container support frame, and a link with a second pivot at one end and a third pivot at the other end, said second pivot engaging 25 said supporting arm and said third pivot engaging said rigid main frame.

30

10. In a tilting bracket for containers having a rigid main frame and a tiltable container support frame, the improvement which includes a track channel formed in said main frame, a first pivot attached to one end of the container support frame and engaged slideably and pivotally with the track channel in said main frame, and a link with a second pivot at one end and a third pivot at the other end, said second pivot engaging said container support frame and said third pivot engaging said rigid main frame.
